(57) **CLAIM**

The ornamental design for a scalpel blade, as shown and described.

DESCRIPTION

FIG. 1 is a perspective view of a scalpel blade in accordance with this design;

FIG. 2 is a side elevation of FIG. 1;

FIG. 3 is a view on the cutting end of the blade of FIG. 2;

FIG. 4 is an end elevation on the non-cutting end ante blade of FIG. 2;

FIG. 5 is a top plan of FIG. 2;

FIG. 6 is an underneath plan of FIG. 2;

FIG. 7 is a perspective view of a second embodiment of scalpel blade in accordance with this design;

FIG. 8 is an elevation of FIG. 7;

FIG. 9 is a view on the cutting end of the blade of FIG. 8;

FIG. 10 is an end elevation on the non-cutting end of the blade of FIG. 8;

FIG. 11 is a top plan of FIG. 8;

FIG. 12 is an underneath plan of FIG. 8;

FIG. 13 is a perspective view of a third embodiment of scalpel blade in accordance with this design;

FIG. 14 is an elevation of FIG. 13;

FIG. 15 is a view on the cutting end of the blade of FIG. 14;

FIG. 16 is an end elevation on the non-cutting end of the blade of FIG. 14;

FIG. 17 is a top plan of FIG. 14; and,

FIG. 18 is an underneath plan of FIG. 14.

Broken lines shown in the drawings illustrate portions of the scalpel blade, and form no part of the claimed design.
